(57) **CLAIM**

The ornamental design for a card-index holder, as shown and described.

DESCRIPTION

FIG. 1 is a perspective view of a card-index holder showing my new design; in an open position;

FIG. 2 is a perspective view thereof; in a closed position;

FIG. 3 is a right side elevational view thereof;

FIG. 4 is a rear elevational view thereof;

FIG. 5 is a top plan view thereof;

FIG. 6 is a front elevational view thereof;

FIG. 7 is a left side elevational view thereof;

FIG. 8 is a perspective view thereof, similar to FIG. 1 with the card-index removed;

FIG. 9 is a front elevational view of FIG. 8; in a closed position; and,

FIG. 10 is a right side elevational view of FIG. 8; in a closed position.

The broken lines showing of card-index are for illustrative purpose only and forms no part of the claimed design.
